DESIGN FOR A PERFUME BURNER LAMP

Irving W. Rice, New York, N. Y., assignor to
Irving W. Rice & Co., New York, N. Y.

Application February 27, 1936, Serial No. 61,381

Term of patent 3½ years

To all whom it may concern:

Be it known that I, Irving W. Rice, a citizen of the United States, residing in the Borough of Manhattan, city, county, and State of New York, have invented a new, original, and ornamental Design for a Perfume Burner Lamp, of which the following is a specification, reference being had to the accompanying drawing, forming part thereof.

The figure is a perspective view of a perfume burner lamp, showing my new design. The ap-

pearance of the opposite sides of the design is substantially the same as the side disclosed.

The dominant feature of my design resides in the contour shown in full lines.

The portions of the design indicated by stippling are opaque.

I claim:

The ornamental design for a perfume burner lamp as shown and described.

IRVING W. RICE.
